CONTAINER FOR LIQUIDS

Leard Evander Lisk, Jr., Summerfield, N.C., assignor to
Lisk Enterprises Corporation, Greensboro, N.C.

Filed Oct. 8, 1971, Ser. No. 187,929

Term of patent 14 years

Int. Cl. D9—03

U.S. Cl. D9—175

FIG. 1.

FIG. 2.

FIG. 3.

FIG. 1 is a top perspective view of a container for liquids showing my new design;

FIG. 2 is a bottom perspective view; and

FIG. 3 is a bottom plan view thereof.

The broad side opposite that seen in FIG. 1 is plain and unornamented and the narrow side not seen is textured like the narrow side seen in FIGS. 1 and 2 and is a mirror image thereof.

The broad side opposite the side illustrated in FIG. 1 is plain and unadorned as illustrated in FIG. 3. The narrow side opposite the narrow side illustrated in FIGS. 1 and 2 is textured and is a mirror image of the narrow side illustrated in FIGS. 1 and 2.

I claim:

The ornamental design for a container for liquids, as shown and described.
